UNITED STATES PATENT OFFICE

VICTOR S. PEARLMAN, OF CHICAGO, ILLINOIS, ASSIGNOR TO THE VICBRIDGE LAMP COMPANY, OF CHICAGO, ILLINOIS, A CORPORATION OF ILLINOIS

DESIGN FOR A COMBINED CARD TABLE LAMP AND TRAY

Application filed August 15, 1932. Serial No. 44,613. Term of patent 14 years.

To all whom it may concern:

Be it known that I, VICTOR S. PEARLMAN, a citizen of the United States of America, residing at Chicago, in the county of Cook, and State of Illinois, have invented a new, original, and ornamental Design for a Combined Card Table Lamp and Tray, of which the following is a specification, reference being had to the accompanying drawing, forming a part thereof.

The drawing is a view in perspective of a combined card table lamp and tray showing my new design.

I claim:

The ornamental design for a combined card table lamp and tray, substantially as shown.

VICTOR S. PEARLMAN.
